CLAIM

The ornamental design for a fishing rod grip, as shown and described.

DESCRIPTION

FIG. 1 is a top plan view of a fishing rod grip showing my new design;

FIG. 2 is a right side elevational view thereof, the opposite side being a mirror image of the same;

FIG. 3 is a bottom plan view thereof;

FIG. 4 is a front elevational view thereof; and

FIG. 5 is a rear elevational view thereof.
